UNITED STATES PATENT OFFICE.

WILLIE LEE CHAMBERS, OF LOS ANGELES, CALIFORNIA, ASSIGNOR TO WILLIAM H. HOEGEE CO., INC., OF LOS ANGELES, CALIFORNIA, A CORPORATION OF CALIFORNIA.

FRUIT-PICKER'S BAG.

Application filed June 30, 1924. Serial No. 723,330.

My invention relates to fruit pickers' bags, and a purpose of my invention is the provision of a bag which is structurally simple and extremely durable, and which includes means by which the entrance end of its mouth is held open, but with sufficiently yielding action to allow the upper edge of the bag to readily conform to the contour of that portion of the picker's body which it engages, whereby the usual discomfort incident to the use of other bags is entirely eliminated.

I am aware that bags have been heretofore proposed in which they aimed to eliminate such discomfort, but the frames provided for maintaining the bag mouth in open position have not been sufficiently flexible or resilient to allow the back upper edge of the bag to conform to the contour of the body of the picker. This is particularly true of the bags designed for use in the picking of cantaloupes or any other fruit in which it is necessary to bend the body forwardly when picking the fruit, thus exerting a body pressure against the back edge of the bag, which sets up great discomfort.

I will describe only one form of fruit picker's bag embodying my invention, and will then point out the novel features thereof in claims.

In the accompanying drawings:

Figure 1 is a view showing in perspective one form of fruit picker's bag embodying my invention;

Figure 2 is a detail perspective view showing the means for maintaining the bag mouth in open position;

Figures 3 and 4 are vertical sectional views taken on the lines 3-3 and 4-4, respectively, of Figure 1.

Referring specifically to the drawings, in which similar reference characters refer to similar parts, my invention in its present embodiment includes a bag body designated at B, which is formed of flexible material and which has its lower end open, but normally closed by bending the same upwardly in the usual manner, as clearly illustrated in Figure 1. The upper end of the bag body is maintained in open position at all times by means of a frame designated generally at F and which, as shown in Figure 2, comprises a single length of resilient wire bent to form arcuate rods 15 and 16 co-extensive in length and disposed in spaced parallel

relation, with their ends rigidly connected. The ends of the wire of which the frame is formed terminate in eyes 17 which are permanently connected. The rods 15 and 16 are maintained against spreading by straps 18 formed of leather or other suitable material and riveted in the form of loops, as clearly shown in Figure 2. The upper rod 15 is bent upon itself to provide eyes 19 arranged in pairs adjacent the opposite ends of the frame for the purpose of receiving hangers or brackets 20. Each bracket 20 is formed of a single length of wire bent in substantially U-form, with its extremities provided with hooks 21 and its medial portion with an eye 22 which is adapted to be engaged by a hook 23 carried by a supporting strap 24.

The resilient frame F is held in substantially U- or semi-circular form by means of a connecting strip K which, in the present instance, is formed of leather or other suitable material and bent upon itself and riveted at its ends to provide loops 25 which receive the vertical end portions of the frame F. The length of the connecting strip K is such that the frame F is held under tension, that is to say, the ends of the frame are slightly contracted against their tendency to expand, wherefore it will be seen that the connecting strip is held in fully extended position, but yieldable, so as to allow the necessary flexing of the strip to perform the purpose for which it is designed.

In the applied position of the frame F within the upper or mouth edge of the bag body, the edge portion of the flexible material of which the bag body is formed is folded over the frame and then stitched as indicated in Figure 1, and as clearly shown in Figure 4. To reinforce the stitching and thus maintain the frame in proper position, sheets 26 of leather or other suitable material are extended over the edge and riveted or otherwise secured so that the frame is securely held in the edge of the bag. The connecting strip K is associated with the mouth edge in a manner similar to that of the frame F in that the upper edge portion of the bag body is folded upon itself and stitched so as to provide an edge pocket in which the strip is received. This arrangement is clearly shown in Figure 3.

For reinforcing that edge of the bag mouth through which the connecting strip

K extends, and which edge will be herein-after referred to as the back edge, and to pad such edge so as to prevent discomfort to the picker, a sheet 27 of canvas or other suitable material is folded longitudinally upon itself, as shown in Figure 3, and riveted or otherwise secured to the back edge so as to be interposed between the connecting strip K and the body of the picker.

10 The pad so formed is co-extensive in length with the back edge, with its ends extended forwardly to the curved or front edge of the mouth, as clearly illustrated in Figure 1.

With the frame F in applied position 15 within the front edge of the mouth, the eyes 19 are extended through suitable openings formed in the front edge so as to be associated with the supporting hangers or brackets 20 and to permit the subsequent 20 application of the supporting strap 24 to the hangers.

The open lower end of the bag body B is adapted to be held in closed position by a cord or rope which includes two strands 25 28 and 29 provided at their lower ends with rings 30 secured in looped straps 31 riveted to the bag body. The strands 28 and 29 are knotted at the point indicated at 32 to secure a ring 33 thereon, and this ring is 30 adapted to engage a hook 34 secured to the upper edge of the bag mouth by a strap 35.

By this arrangement it will be seen that when the ring 33 engages the hook 34, the 35 rope operates to maintain the lower end of the bag in closed position.

In practice, the back edge of the bag mouth reposes against the body of the picker, and during the picking of the fruit from the ground, it is necessary that the 40 picker lean forwardly, thus exerting a pressure against the back edge of the bag. By virtue of the resilient frame F the connecting strip K is supported so as to yield to any pressure exerted thereon and to thus 45 permit the strip as well as the pad 27 to conform to that portion of the picker's body engaging the back edge. In this manner the discomfort caused by the usual rigid back edge pressing against the picker's body is 50 eliminated, while at the same time the resilient frame functions to properly maintain the bag mouth in open position.

Although I have herein shown and described only one form of fruit picker's bag 55 embodying my invention, it is to be understood that various changes and modifications may be made herein without departing from the spirit of the invention and the spirit and scope of the appended claims.

60 What I claim is:

1. A bag of the character described comprising a body of flexible material, and

means for maintaining the mouth of the bag in open position, including a bowed resilient member, and a flexible member connecting the ends of the resilient member and capable of being drawn taut so as to flex the resilient member to conform to an arc and hold the same tensioned. 65

2. In a bag of the character described, a frame of arcuate form comprising a single length of wire bent upon itself to provide curved portions disposed in spaced parallel relation and each portion looped at predetermined points to form eyes, and a strip of flexible fibrous material looped about the ends of the curved portions and spanning the ends of the frame. 70

3. A bag of the character described, as embodied in claim 2, wherein the strip of flexible material is associated with the frame in such manner that the frame is held in tension by the strip and the strip 80 fully extended.

4. A bag of the character described comprising a body of flexible material, an arcuate frame formed of resilient wire secured within the mouth edge of the bag and including spaced rods, one of which is formed with eyes, a flexible strip of fibrous material 85 connecting the ends of the frame and disposed within the mouth edge of the bag, hangers secured to the eyes, a supporting strap having hooks secured to the hangers, and a flexible pad secured to that edge of 90 the bag mouth in which the flexible strip is contained. 95

5. A bag of the character described comprising a body of flexible material, an arcuate frame formed of resilient wire secured within the mouth edge of the bag and including spaced rods, one of which is formed with eyes, a flexible strip of fibrous material connecting the ends of the frame and disposed within the mouth edge of the bag, 100 hangers secured to the eyes, a supporting strap having hooks secured to the hangers, a flexible pad secured to that edge of the bag mouth in which the flexible strip is contained, and sheets of flexible material 105 secured to the edge of the bag mouth and embracing the frame, for the purpose described. 110

6. In a bag of the character described, a frame of arcuate form comprising a single 115 length of wire bent upon itself to provide curved portions disposed in spaced parallel relation and each portion looped at predetermined points to form eyes, and a strip of slightly extensible woven material looped about the ends of the curved portions and spanning the ends of the frame. 120
